UNITED STATES PATENT OFFICE.

DARIUS V. MARTIN, OF WILDWOOD, NEW JERSEY.

PEDESTAL.

Application filed June 29, 1926. Serial No. 119,290.

My invention relates to pedestals for supporting objects to be knocked down in a ball throwing game.

The objection to the usual supports for objects is that, when a thrown ball strikes the support, it rebounds directly back toward the thrower and the spectators and is likely to injure them.

The object of my invention is to provide a pedestal for supporting objects which when struck by a thrown ball, will cause the ball to rebound in a direction other than toward the thrower.

This object, and other advantageous ends which will be described hereinafter, I attain in the following manner, reference being had to the accompanying drawings in which—

Figure 1 is a front elevation of a pedestal having objects mounted thereon,

Figure 2 a plan view of the pedestal shown in Figure 1,

Figure 3 a side elevation of the pedestal shown in Figure 1,

Figure 4 an enlarged section on line 4—4 of Figure 1,

Figure 5 an enlarged section partly in full on line 5—5 of Figure 1,

Figures 6 and 7 plan views of modified forms of pedestals,

Figure 8 a section on line 8—8 of Figure 7 drawn on a smaller scale, and

Figures 9 and 10 sections of modified forms of standards which form a part of my invention.

Referring to the drawings, 1 indicates a base adapted to be secured to the floor, 2 a standard secured to the base and extending above the floor, 3 a platform secured to the upper end of the base, and 4 objects, which may be in the shape of milk bottles or other shapes, stacked on the platform.

Base 1 may be of any suitable design having a flange 5, through which bolts may pass for securing it to the floor, and a boss 6 in which standard 2 may be secured.

Standard 2 is of such cross section that a thrown ball striking the standard will rebound in a direction other than toward the thrower as indicated in dot-and-dash lines in Figures 4, 9 and 10. This cross section may be circular, as shown in Figure 4, or may be in the forms shown in Figures 9 and 10, which have their side faces diverging from the front toward the rear. The standard is preferably of circular cross section as

it enables the use of an ordinary pipe which may be threaded at its lower end and screwed into boss 6 and also threaded at its upper end and screwed into a flange 7 to which platform 3 may be secured.

The platform has a recess 8 in which flange 7 is disposed and secured to the platform by bolts 9. The upper face 10 of the platform may be of any shape to properly support objects 4 thereon. For simplicity, this face is preferably flat so that the stacked objects 4 may rest thereon as shown in Figure 1. The under face 11 of the platform is of such shape that a thrown ball striking the face will rebound downwardly, as indicated by the dot-and-dash lines in Figure 3. This face may be curved as shown in Figure 5 or flat and inclined inwardly and downwardly as shown in Figure 8. Other forms of under faces may be provided and all will function equally well so long as they diverge from the edge 12 of the upper face.

Platform 3 is preferably made of hard wood and its edge 12 is reinforced by a metallic strip 13 to prevent wear which would be caused by the thrown ball striking the edge. The rear edge 14 of the upper face is also reinforced by a metallic strip 15 to prevent wear which would be caused by objects 4 striking the edge when knocked down by a thrown ball.

The outline of the upper face, as shown in plan in Figure 2, is straight at edge 14 and curved at edge 12. The outline may also be as shown in Figures 6 and 7, but in each case the thrown ball striking edge 12, will rebound in a direction other than toward the thrower.

When used in a ball throwing game, objects 4 are stacked on the platform and a ball is thrown at the objects. Should the ball strike the platform or the standard, it will be deflected downwardly or to one side.

It will be seen from the foregoing that my pedestal when used in any ball throwing game, avoids the danger of causing injury to the thrower or the spectators by balls rebounding back toward the thrower, and that it is equally effective on balls thrown at any speed.

While I have described my invention as taking a particular form, it will be understood that the various parts may be changed without departing from the spirit thereof, and hence I do not limit myself to the precise

construction set forth, but consider that I am at liberty to make such changes and alterations as fairly come within the scope of the appended claims.

Having thus described my invention, what I claim as new and desire to secure by Letters Patent is:—

1. In a game in which a ball is thrown with the object of knocking targets from a support, a pedestal adapted when hit by a thrown ball to deflect the ball downwardly or to one side including a standard having its side faces diverging from the front toward the rear, and a platform on the standard adapted to support the targets on its upper face and having its under face diverging from the edge of the upper face.

2. In a game in which a ball is thrown with the object of knocking targets from a support, a pedestal adapted when hit by a thrown ball to deflect the ball downwardly or to one side including a standard of circular cross section, and a platform on the standard adapted to support the targets on its upper face and having its under face diverging from the edge of the upper face.

3. In a game in which a ball is thrown with the object of knocking targets from a support, a pedestal adapted when hit by a thrown ball to deflect the ball downwardly or to one side including a standard having its side faces diverging from the front toward the rear, and a platform on the standard adapted to support the targets and having a flat upper face and an inwardly and downwardly curved under face.

4. In a game in which a ball is thrown with the object of knocking targets from a support, a pedestal adapted when hit by a thrown ball to deflect the ball downwardly or to one side including a standard having its side faces diverging from the front toward the rear; a platform on the standard adapted to support the targets on its upper

face and having its under face diverging from the edge of the upper face, and a reinforcing strip secured to the front edge of the platform.

5. In a game in which a ball is thrown with the object of knocking targets from a support, a pedestal adapted when hit by a thrown ball to deflect the ball downwardly or to one side including a standard having its side faces diverging from the front toward the rear; a platform on the standard adapted to support the targets on its upper face and having its under face diverging from the edge of the upper face, and a reinforcing strip secured to the rear edge of the platform.

6. In a game in which a ball is thrown with the object of knocking targets from a support, a pedestal adapted when hit by a thrown ball to deflect the ball downwardly or to one side including a platform adapted to support the targets having a recess, the upper face of the platform being flat and the under face curved inwardly and downwardly; a standard having its upper end in the recess; means for securing said end to the platform, and a base secured to the lower end of the standard.

7. In a game in which a ball is thrown with the object of knocking targets from a support, a pedestal adapted when hit by a thrown ball to deflect the ball downwardly or to one side including a platform adapted to support the targets having a recess in its under side, its upper face flat and its under face curved inwardly and downwardly; a pipe; a flange secured to the upper end of the pipe and disposed in the recess; means passing through the platform and the flange for securing it to the platform, and a base secured to the lower end of the pipe.

In testimony whereof I have signed my name to this specification.

DARIUS V. MARTIN.
